UNITED STATES PATENT OFFICE

SIMEON E. TRAVIS, JR., OF HATTIESBURG, MISSISSIPPI, ASSIGNOR TO THE WELDMECH
STEEL PRODUCTS CO., A CORPORATION OF MISSISSIPPI

METALLIC TRUCK BODY

Application filed January 23, 1928. Serial No. 248,839.

This invention relates to a metallic truck body designed primarily for the haulage of boxes or crates of bottled goods, but it is to be understood that a truck body in accordance with this invention may be employed for the haulage of any objects for which it is found applicable, and the invention has for its object to provide, in a manner as hereinafter set forth, a truck body having a reinforced and unusually durable bottom constructed to reduce damage thereto when loading to a minimum, to prevent in case of liquid leaking thereon from a crate, box or barrel during haulage the liquid from spreading and damaging adjacent crates, boxes or barrels, and further to provide for drainage therefrom in case of liquid leaking thereon.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a top plan view of a truck bottom or deck in accordance with this invention.

Figure 2 is a section on line 2-2 Figure 1.

Figure 3 is a section on line 3-3 Figure 1.

Figure 4 is a fragmentary view in plan of a modified form.

Figure 5 is a cross sectional view of still another modified form.

Figure 6 is a fragmentary view in plan illustrating the flooring provided with drainage openings.

A truck bottom or deck in accordance with this invention includes side and end sills and a corrugated flooring secured to the sills. With reference to Figures 1 to 5 the sills are in the form of angle irons having vertical and horizontal legs and with the flooring secured to and upon the horizontal legs and of less height than the vertical legs. The end sills

are indicated at 1, 2 and the side sills at 3, 4. The vertical legs of the sills are designated 5 and the horizontal legs 6.

With reference to Figure 1 the flooring is indicated at 7 and abuts against the vertical legs 5 of the side sills 3, 4. The flooring 7 is transversely corrugated as indicated at 8 and in longitudinal section the flooring 7 consists of oppositely disposed V-shaped portions. The flooring 7 has its ends extend upon the horizontal portions of the end rails and also abut against the vertical portions thereof. Extending lengthwise of the lower face of the flooring 7 are T-shaped brace members 9 arranged in spaced relation and which have the end portions of the heads thereof cut away so that the remaining portions of the heads will abut against the lower face of the flooring. The end portions of the stems of the members 9 are welded against the lower face of the horizontal portions of the end sills. The corrugations provide channels 10 for collecting leakage and to prevent the spreading of the leakage throughout the upper face of the flooring.

The form shown in Figure 4 is the same as that shown in Figure 2, with this exception that the flooring 11 is lengthwise corrugated and the T-shaped brace members 12 are disposed transversely with respect to the flooring. The lengthwise corrugations of the flooring 11 are indicated at 13 and the channels provided by the corrugations are designated 14. The T-shaped brace members 12 have the end portions of their heads cut away so that the remaining portions of the heads can be secured to the lower face of the flooring 11. The end portions of the stems of the braces are secured to the horizontal legs of the side sills 3, 4.

The form shown in Figure 5 is the same as that shown in Figure 4, with the exception that the corrugations of the flooring, indicated at 15, are semi-circular in cross section as indicated at 16. The channels provided by the corrugated flooring 15 are indicated at 18. The T-shaped brace members 19 employed in the form shown in Figure 5 are set up in the same manner as the form shown in Figure 4.

The floorings are provided with drainage openings, at the bottom of the channels formed in the upper face of the flooring, and by reference to Figure 6 a corrugated flooring 5 is indicated at 26 and provided with drainage openings 27 at the bottom of the channels 28. It is to be understood that the drainage openings 27 can be positioned at any suitable point or points throughout the flooring.

19 It is thought the many advantages of a truck bottom or deck, constructed in accordance with this invention, can be readily understood, and although the preferred embodiments of the invention are as illustrated and 15 described, yet it is to be understood that changes in the details of construction can be had which fall within the scope of the invention as claimed.

What I claim is:

20 1. A truck body comprising side and end sills, each of said sills being of angle-shaped cross section to provide a vertical and a horizontal leg, said horizontal legs extending inwardly from the lower ends of said vertical 25 legs, a corrugated flooring secured to said sills, abutting the upper faces of the horizontal legs and the inner faces of the vertical legs, and spaced, parallel brace members secured to the lower faces of the horizontal legs 30 of opposed sills and to the lower bends of said flooring, the lower bends in said flooring provided with spaced drain openings.

2. A truck body comprising side and end sills, each of said sills being of angle-shaped 35 cross section to provide a vertical and a horizontal leg, said horizontal legs extending inwardly from the lower ends of said vertical legs, a flooring corrugated throughout and secured to said sills and having its edges 40 sealed by said vertical legs, T-shaped brace members having the end portions of the heads thereof cut away, the remaining portions of the heads of said brace members positioned against the lower faces of the lower bends of 45 said flooring, said remaining portions of the heads of said brace members positioned between the horizontal legs of opposed sills, and said brace members being secured to the lower faces of the horizontal legs of opposed sills 50 between which the remaining portions of the heads of the brace members are arranged.

3. A truck body comprising side and end sills, each of said sills being of angle-shaped cross section to provide a vertical and a horizontal leg, said horizontal legs extending inwardly from the lower ends of said vertical legs, a flooring corrugated throughout and secured to said sills and having its edges sealed by said vertical legs, T-shaped brace 55 members having the end portions of the heads thereof cut away, the remaining portions of the heads of said brace members positioned against the lower faces of the lower bends of said flooring, said remaining portions of the heads of said brace members positioned 60 65

between the horizontal legs of opposed sills, said brace members being secured to the lower faces of the horizontal legs of opposed sills between which the remaining portions of the heads of the brace members are arranged, and 70 said flooring having the lower bends thereof provided with spaced drain openings.

4. A truck body comprising side and end sills, each of angled shape cross section to provide a vertical and a horizontal leg, said horizontal legs extending inwardly from the lower ends of the vertical legs, a flooring corrugated throughout, extending upon and secured to opposed horizontal legs and opposing the inner faces of opposed vertical legs, 75 said flooring having its upper bends positioned below the upper ends of the vertical legs and its lower bends positioned throughout above said horizontal legs, the said lower bends being provided with drain openings, 80 and brace members secured to opposed horizontal legs and having their tops positioned below said lower bends.

In testimony whereof, I affix my signature hereto.
